UNITED STATES PATENT OFFICE.

LULA SCHWITZGEBEL, OF CLIFTON, OREGON.

BUTTON-HOOK.

1,242,248.

Specification of Letters Patent.

Patented Oct. 9, 1917.

Application filed March 8, 1917. Serial No. 153,345.

To all whom it may concern:

Be it known that I, LULA SCHWITZGEBEL, a citizen of the United States, residing at Clifton, in the county of Clatsop, State of Oregon, have invented certain new and useful Improvements in Button-Hooks; and I do hereby declare the following to be a full, clear, and exact description of the invention, such as will enable others skilled in the art 10 to which it appertains to make and use the same.

This invention relates to improvements in buttoners and has for an object the provision of a buttoner by which shoes or the 15 like may be readily fastened with but little strain so that loosening of the button and stretching of the button hole will be prevented.

A further object of the invention is to provide a buttoner including a member provided with a button engaging hook and means of novel construction and arrangement carried by said member by which the buttoning operation will be greatly facilitated.

Still another object resides in the provision of a buttoner embodying the desired features, of simplicity, efficiency and reliability, is convenient of manipulation and 30 may be manufactured and marketed at a relatively low cost.

With the above and other objects of similar nature in view, the invention consists in the construction, combination and arrangement of parts, set forth in and falling within the scope of the appended claims.

In the drawing:

Figure 1 is a perspective view of a buttoner constructed in accordance with the 40 preferred embodiment of the invention,

Figs. 2 and 3 are elevational views illustrating the manner of manipulating the buttoner, and

Fig. 4 is a perspective view of a modified 45 form of the invention.

Referring now more particularly to the accompanying drawing, there is illustrated in Figs. 1, 2 and 3 a buttoner constructed in accordance with the preferred embodiment 50 of the invention.

In this form of the invention, the buttoner consists of a handle 5, enlarged at one end as shown at 6 and formed at its opposite end with a hook 7 the bight portion of which is 55 provided with a pair of spaced channels 8 extending transversely therearound. A

lever 9 in the form of a flat metal plate is carried by the handle 5 and is provided at one end with spaced fingers 10 bent around the bight portion of the hook and loosely engaged in the channels 8 so as to pivotally support the lever for swinging movement longitudinally with respect to the handle.

The lever 9 further consists of a head 11 from which the fingers 10 are formed while 65 extending from the head at the opposite side from the fingers is an outwardly tapered body portion 12 resulting in a reduced neck 13 adjacent the head 11.

In Fig. 4 of the drawing in which there is 70 illustrated a modified form of the invention, the handle 5 and hook 7 are constructed as in the preferred embodiment shown in Fig. 1 with the exception that the channels 8 are omitted, the terminal of the bill portion of 75 the hook being provided with a reduced portion 14 and the handle provided with a reduced portion 15 adjacent the hook. In this form of the invention the lever is of a somewhat different construction, it being 80 provided with extensions 16 diverging from the neck 13 in the opposite direction from the body portion 12 and terminally provided with elongated openings 17 loosely receiving the reduced portions 14 and 15. The lever 85 is thus free to swing longitudinally with respect to the handle as is evident.

The manner of manipulating both forms of the invention is identical and an illustration of their use has, therefore, been limited to the preferred embodiment. Referring to Figs. 2 and 3 there is shown a fragment of an article such as a shoe which is fastened together by the means of buttons. In employing the buttoner, the lever is positioned as shown in Fig. 2 and the hooked end of the handle inserted through the button hole 18 and engaged in the usual manner with the button 19. When so positioned, the button hole will also have passed over 100 the lever 9 until it embraces the neck 13 thereof in being limited in further movement by the tapered portion of the body 12. The body of the lever is then grasped and the latter swung on its pivotal connection 105 with the hook whereby to carry the button hole 18 over the button 19 as shown in Fig. 3 of the drawing, the lever at the same time passing from the button hole so that detachment of the buttoner may be effected merely 110 by disengaging the hook from the button in the usual manner.

2
What I claim is:

1. A buttoner including a handle provided with a button engaging hook at one end, and a lever pivoted to the hooked end 5 of the handle.
2. A buttoner including a handle provided with a button engaging hook at one end, and a lever pivoted to the hooked end of and arranged to swing longitudinally 10 with respect to the handle.
3. A buttoner including a handle provided with a button engaging hook at one

end, and a lever carried by and insertible with the hooked end of the handle through a button hole provided member and movable 15 to pass said button hole over a button engaged by the hook.

In testimony whereof, I affix my signature, in the presence of two witnesses.

LULA SCHWITZGEBEL.
